SOAP DISPENSING SHAVING BRUSH OR
THE LIKELouis V. Aronson, Newark, N. J., assignor to Art
Metal Works, Inc., a corporation of New
Jersey

Application June 11, 1932. Serial No. 616,631

8 Claims. (Cl. 15—138)

This invention relates to improvements in dispensing devices for shaving brushes or the like.

Among the objects of this invention are the provision of improved means for dispensing material from a reservoir, provided in a handle, into a brush or the like; the provision of a follower operated by air pressure; the provision of a pump for creating air pressure for advancing a follower to dispense soap or the like; the provision of means for controlling the rate at which air is built up in the space behind the follower; and generally the provision of improved means for dispensing soap into a brush.

Other objects of the invention will appear from the following description taken in connection with the drawing, in which

Fig. 1 is a disassembled view of a shaving brush including a handle used as a container and provided with dispensing means constructed according to a preferred embodiment of the invention;

Fig. 2 is a vertical central section of the assembled shaving brush;

Fig. 3 shows the pump controlling valve as viewed from the line 3—3 of Fig. 2, part of the valve being in section; and

Fig. 4 is a cross section through the handle on the line 4—4 of Fig. 2 showing the valve for closing or controlling the effective size of the passage through which soap is delivered into the brush.

For the purposes of disclosing my invention I have illustrated one preferred embodiment of the invention as a shaving brush which includes a barrel 5 made of any suitable transparent material, and which is preferably exteriorly threaded at its lower end to receive a bottom closure member 6, which together provide a reservoir 7 for soap against which operates a follower 8 provided with a rubber sealing member 9 held in position by a plate washer 10 which may be drawn toward the follower 8 by means of the screw 11 by means of which the sealing effect between the rubber member 9 and the barrel 5 may be controlled.

The bottom member 6 is preferably threaded interiorly to receive a brush retaining ring 12 which is preferably shouldered, as indicated, to engage over a shoulder on a ring 13 in which the brush 14 is set.

Communication between the reservoir 7 and the brush 14 is established by providing the bottom member 6 with a conduit 15 which preferably registers with a tube 16 which may be of rubber or any suitable material and may be secured in the base of the brush by any suitable means.

The effective cross sectional area of the conduit 15 may be controlled by means of a screw 17 which may be advanced and retracted. The forward end 18 of the screw 17 is of the same diameter as the conduit 15, and for the purpose of employing this screw for shutting off the flow of soap entirely the conduit 15 is provided with a lateral recess 19 into which the end 18 of the screw 17 may be advanced, as clearly apparent from Figs. 2 and 4.

The other end of the barrel 5 is preferably also threaded exteriorly upon which is threaded a top closure member 20 which is provided with a cylindrical flange 21 constituting a pump cylinder in which operates a piston designated generally at 22. The free end of the cylinder 21 may be threaded exteriorly to receive the end closure member 23. This member may be provided with a port 24 which communicates with a valve chamber 25 provided with a port 26 which may be controlled by a screw 27 by means of which the rate of flow of air from the pump chamber to the space behind the piston may be controlled, for the purpose of adjusting the operation of the pump to build up any suitable desired pressure on the follower 8.

The piston 28 comprises a metallic disk 29, a flexible pump washer 30, and a clamping disk 31 connected by a screw 32 to a plunger 33 which extends through the opening in the top closure member 20, and which is connected exteriorly of this member by means of a screw 34 to a manipulative member 35 which is preferably provided with a skirt portion 36 slidably engaging the exterior of the top closure member 20.

The top closure member 20 and the manipulative member 35 are provided with ports 37 and 38 by means of which air may be admitted behind the piston 22 as the piston is advanced and into the space between these members as the piston is retracted. Upon retraction of the piston the air admitted into the space behind the piston will be forced past the washer 30 into the pump chamber. Upon advancing the piston, air is forced from the pump chamber into the space behind the follower 8 and when sufficient pressure is established in this space the follower 8 will be advanced forcing the soap into the brush.

When the brush is not in use the conduit 15 may be closed to prevent any accidental feeding of the soap. The pump device may be operated by holding the barrel in one hand and by grasping the manipulative member 35 with the other hand and reciprocating the same. For the purpose of facilitating assembly and operation, the 110

end member 6, the head of the screw valve 17 and the manipulative member 35 may be roughened, milled, or corrugated, as indicated. By suitable adjustment of the screw valves 17 and 27 the effective opening of the tube 15 may be decreased and the pressure operating on the soap may be increased, to cause the soap to be forced far into the brush.

While the principles of the invention have been described with reference to the single embodiment shown in the drawing and with reference to a particular use, it is to be understood that the several features of the invention may be embodied in different forms for different uses, that it is not the intention to limit the claims to the particular embodiment disclosed, and that any terms imported from the specification into the claims are to be considered as words of description rather than of limitation.

20 What is claimed as new and desired to be secured by Letters Patent of the United States is:

1. A handle comprising means for supporting a brush and provided with a reservoir for containing material to be dispensed to the brush and 25 with a conduit for carrying said material to said brush, a follower within said handle operating against said material, a pump comprising a cylinder, said cylinder including an end wall of larger diameter than said cylinder providing for 30 a threaded connection between said end wall and said handle for securing said cylinder within said handle, and a piston rod operable in an aperture in said end wall for building up pressure against the rear side of said follower.

35 2. A handle comprising means for supporting a brush and provided with a reservoir for containing material to be dispensed to the brush and with a conduit for carrying said material to said brush, a follower within said handle operating against said material, a pump secured to said handle for building up pressure against the rear side of said follower, means for adjusting the effective size of the conduit through which the material is delivered to the brush, and means 45 for controlling the rate of flow of air from the pump to the space behind the follower.

3. A handle comprising means for supporting a brush and provided with a reservoir for containing material to be dispensed to the brush and 50 with a conduit for carrying said material to said brush, a follower within said handle operating against said material, a pump for building up pressure against the rear side of said follower, said pump including a cylinder secured to and 55 projecting into said handle and having a smaller external diameter than the internal diameter of said handle, a piston in said cylinder, and means accessible from the exterior for operating said piston.

60 4. A handle comprising means for supporting a brush and provided with a reservoir for containing material to be dispensed to the brush and with a conduit for carrying said material to said brush, a follower within said handle operating 65 against said material, a pump for building up

pressure against the rear side of said follower, said pump including a cylinder arranged concentrically with and projecting into said handle, means for securing said cylinder to said handle, a piston in said cylinder, and means accessible from the exterior for operating said piston, said means comprising a cup shaped member surrounding and enclosing one end of said handle.

5. A handle provided with means for supporting a brush and with a chamber for receiving material to be dispensed to said brush, a follower operating on said material, a pump including a pump cylinder located wholly within said handle, for building up air pressure against the rear face of said follower, a piston in said pump cylinder, a circumferential cylindrical flange on said pump cylinder threadedly engaging the exterior of said handle with its outer surface projecting radially outwardly beyond the outer surface of said handle, and an open ended cylindrical manipulative member secured to said piston and slidably engaging said flange.

6. A handle provided with means for supporting a brush and with a chamber for receiving material to be dispensed to said brush, a follower operating on said material, a pump including a pump cylinder located wholly within said handle, for building up air pressure against the rear face of said follower, a piston in said pump cylinder, and a manipulative member for operating said piston located exteriorly of said handle and provided with a skirt portion surrounding the adjacent end of said handle.

7. A handle provided with means for supporting a brush and with a chamber for receiving material to be dispensed to said brush, a follower operating on said material, a pump including a pump cylinder located wholly within said handle, for building up air pressure against the rear face of said follower, a piston in said pump cylinder, and a manipulative member for operating said piston located exteriorly of said handle and provided with a skirt portion surrounding the adjacent end of said handle, said manipulative member and the adjacent end of said pump cylinder being provided with ports for admission of air into the space between said member and the adjacent end of said handle during the return stroke of said pump and admitting air into said pump cylinder behind said piston under pressure created by said manipulative member as said piston is advanced.

8. A handle provided with means for supporting a brush and with a chamber for receiving material to be dispensed to said brush, a follower operating on said material, a pump including a pump cylinder located wholly within said handle for building up air pressure against the rear face of said follower, and a piston in said pump cylinder, the end wall of said pump cylinder being provided with an aperture permitting air to flow from the pump cylinder into the space behind the follower and vice versa.
